UNITED STATES PATENT OFFICE.

HENRY CLAY BASCOM AND ROBERT GALBRAITH, OF LANSINGBURG, NEW YORK, ASSIGNORS TO SAID HENRY CLAY BASCOM.

DESIGN FOR A COOKING STOVE OR RANGE.

SPECIFICATION forming part of Design No. 20,240, dated October 28, 1890.

Application filed October 15, 1889. Serial No. 327,128. Term of patent 14 years.

To all whom it may concern:

Be it known that we, HENRY CLAY BASCOM and ROBERT GALBRAITH, citizens of the United States, residing in the village of Lansingburg, in the county of Rensselaer and State of New York, have jointly invented and produced a new and original Design for Cooking Stoves and Ranges, of which the following is a specification, reference being had to the accompanying drawing, which represents a perspective view of a cooking stove or range having our said design.

The leading feature of this design is the convexly-curved shapes of the border parts of the principal exposed portions of the cooking stove or range, the same comprising the projecting convexly-curved border *a* *g* of the bottom or base, the convexly-curved lower border part *b*, the convexly-curved upright rear border portion, the convexly-curved lower forward end part of the side *d*, the convexly-curved lower front part *h*, and the overhanging border *f* of the top. In harmony therewith, the border *i* of the hearth, the borders of the side panels and oven-door *c*, and the forward border at the side of the rear exten-

sion *p* are all curved convexly, as are the legs *q*, the upper front projection *o*, and the upper border *n* of the front door, which latter has its parts *m*, *l*, *k*, and *j* shaped in pleasing contrast. The ornamentation of the rear extension *p*, legs *q*, and panel *r*, and the surface ornamentations *s* *t* *u* (represented in the accompanying illustration) are not essential or material parts of this design. 35

What we claim is—

In a design for a cooking stove or range, the design for the body thereof, embracing the convexly-curved border of the base, the convexly-curved lower, rear, and forward border portions of the side, the convexly-curved lower front end, and the overhanging border of the top, as shown and described. 40

In testimony whereof we hereunto set our hands, in the presence of two subscribing witnesses, this 12th day of October, 1889. 45

H. CLAY BASCOM.
ROBERT GALBRAITH.
